H. C. GILMER AND P. L. ROOKLEDGE,
ELECTRIC WARMING DEVICE,
APPLICATION FILED FEB. 5, 1919.

1,319,927.

Patented Oct. 28, 1919.

UNITED STATES PATENT OFFICE.

HAMET C. GILMER AND PERCIVAL L. ROOKLEDGE, OF HOLLISTER, CALIFORNIA.

ELECTRIC WARMING DEVICE.

1,319,927.

Specification of Letters Patent.

Patented Oct. 28, 1919.

Application filed February 5, 1919. Serial No. 275,248.

To all whom it may concern:

Be it known that we, HAMET C. GILMER and PERCIVAL L. ROOKLEDGE, citizens of the United States, residing at Hollister, in the county of San Benito and State of California, have invented new and useful Improvements in Electric Warming Devices, of which the following is a specification.

Our invention is an improvement in electrical warming devices of the type used about the body of patients in the treatment of various ailments, and its objects are:

First, to provide an electric warming device that is light in weight.

Second, to provide an electric warming device in which the heat is maintained at a proper, uniform temperature for any length of time desired.

Third, to provide an electric warming device that may be manufactured at small cost and one in which the heating element can be changed or renewed easily.

With these and other objects in view our invention resides in the novel feature of construction and in the unique arrangement of parts to be hereinafter more fully described and claimed, it being understood that various changes in form, proportion, and minor details of construction may be resorted to within the scope of the appended claims.

For a full understanding of our invention and the merits thereof, reference is to be had to the following description and to the accompanying drawings, forming a part of this specification, in which similar reference characters represent corresponding parts in all the views.

In the drawings:

Figure 1 is a plan view of our electric warming device, parts broken away.

Fig. 2 is a sectional view on line 2—2 of Fig. 1, socket and lamp shown in place, with cord and plug attached.

Fig. 3 is a sectional view on line 3—3 of Fig. 1.

Fig. 4 is a view of another form of our electric warming device showing the body portion cast integral and the threaded neck for receiving the insulating bushing.

Fig. 5 is an enlarged sectional view through the neck as indicated on line 5—5 of Fig. 2.

Fig. 6 is an enlarged, longitudinal, sectional view through the neck and bushing.

Fig. 7 is a sectional view on line 7—7 of Fig. 4.

Fig. 8 is an enlarged view of the insulating bushing showing means for clamping onto the socket.

Fig. 9 is an enlarged view of the exteriorly threaded insulating bushing.

Our improved electric warming device, forming the subject matter of the present invention, consists of a flat, bottle-shaped body portion 1 made of light weight metal or other suitable heat conducting material, said body portion 1 may be made in two dish shaped parts 1^a—1^b and may either be hinged together by a suitable hinge 2 and held closed by suitable clamps or fastenings 2^a; or the parts may be seamed together in various ways common in sheet metal construction, or the body portion 1 may be cast integral.

A neck is shown at 3, integral with the body portion 1 and having a restricted opening or passage 3^a communicating with the inner chamber 4 of the body portion 1. The neck 3 flares out as it extends outward from one end of the body portion, forming a widened mouth 5 having rounded edges 5^a.

A split bushing, made of suitable electric insulating material, is shown at 6 adapted to be screwed in or otherwise removably fastened in the restricted opening 3^a, threads 85 provided for this purpose are shown at 3^b—3^c. A shoulder is shown at 3^d in the neck adapted to engage the bushing when the same is screwed in place. The bushing 6 is provided with annular grooves 7 in the inner walls thereof, adapted to receive the ridges 8 of a suitable incandescent electric light socket 9, said socket being of the usual type having means for fastening shade holders thereon.

The split insulating bushing is clamped onto the socket, in place of the shade holder, by means of small bolts 10.

The distance the neck 3 extends and flares outward is intended to be sufficient to protect the socket 9 from contact with the body of a patient or one using the device.

Into the socket 9, and projecting into the inner chamber 4, is screwed a suitable incandescent electric light globe 11 of the tubular type and of a size or strength suitable to develop the heat required.

In case the body portion 1 is made in two parts hinged together, the bushing 6 is then provided with an annular groove 12 on the outer wall, adapted to engage suitable beads in the neck 3, thus binding the bushing in

place when the two parts 1^a and 1^b are fastened together.

An electric light cord is shown at 13 having a plug 14 of the usual type, adapted to

5 be screwed into an electric light socket of a lighting system whereby our device may be connected therewith.

The operation of our device is as follows:—

10 The bushing 6 is secured to the socket 9 in place of the usual shade holder; a suitable electric light globe 11 is screwed into the socket and then the socket, with the bushing and lamp attached, is secured in place 15 in the neck 3 by screwing into place or clamping the parts together, the lamp globe 11 projecting into the inner chamber 4. A suitable length of electric light cord is attached to the socket and connected with an 20 electric power lighting system and the lamp 11 lighted.

Radiant heat from the lamp globe is transmitted to the body portion 1, thereby keeping it warm or hot, depending upon the 25 size of globe used therein or the amount of electricity allowed to enter said lamp.

Our device may lie flat, stand on end or side, leaning against the body or otherwise be placed about the body of a patient. It 30 being much lighter than the devices for this purpose now in use, it may be placed upon very tender, inflamed or wounded parts of the patient without causing discomforture.

Having thus described our invention what 35 we claim as new and desire to secure by Letters Patent is:—

1. An electric warming device of the class described consisting of a hollow, metal body portion composed of two dish shaped members hinged together; a neck, half of which 40 is integral with each dish shaped member and forming, when assembled, a restricted opening or passage communicating with the interior of said body portion; a bushing of suitable electric insulating material having 45 an annular groove on the outer wall thereof; a bead in the inner wall of the restricted opening of the neck adapted to engage the groove in the bushing; means carried by the 50 neck for fastening the two dish shaped members together and securing said bushing in place, said bushing being adapted to be clamped onto an electric light socket in place

of a shade holder whereby an incandescent electric light globe may be held within said 55 metal body portion, substantially as shown and described.

2. An electric warming device of the class described consisting, in combination with an incandescent electric light socket and globe 60 therefor, of a bottle shaped, hollow, metal body portion, adapted to surround said globe; a neck formed integral with the body portion and having a restricted opening 65 communicating with the interior of said body portion, said neck flaring out as it extends outward from the body portion forming a widened opening adapted to protect the socket; a split bushing composed of suitable insulating material, said bushing 70 being provided with means whereby the same may be clamped to the electric light socket in place of a shade holder and means for removably securing the bushing in the restricted opening in the neck whereby the 75 light globe may be held in place within the body portion, substantially as shown and described.

3. An electric warming device of the class described consisting, in combination with 80 an electric light socket and lamp therefor; of a bottle-shaped, hollow, metal body portion adapted to envelop said lamp; a neck formed integral with said body portion and having an opening communicating with 85 the interior of said body portion, said neck flaring outward as it extends out from one end of the body portion, forming a widened opening adapted to receive and protect the electric light socket; a split bushing 90 composed of insulating material; bolts passing through said bushing, adapted to draw the bushing together whereby the bushing may be clamped onto the electric light socket in place of a shade holder; 95 threads on the outer surface of the bushing; corresponding threads in the neck whereby the bushing may be screwed into said neck; a shoulder at the base of the threads in the neck, adapted to serve as a 100 stop for the bushing to seat against, substantially as shown and described.

In testimony whereof we affix our signatures this 28th day of Jan. 1919.

HAMET C. GILMER.

PERCIVAL L. ROOKLEDGE.
